[57] CLAIM

The ornamental design for a lamp shade, as shown and described.

DESCRIPTION

FIG. 1 is a side elevational view of a lamp shade showing my new design;
FIGS. 2 and 3 are respectively top and bottom plan views thereof;
FIG. 4 is a fragmentary cross-sectional view taken along line 4—4 of FIG. 2;
FIG. 5 is a fragmentary elevational view of the interior surface thereof; and
FIG. 6 is a fragmentary cross-section of a second embodiment of my design which is identical to the first embodiment in exterior surface configuration but which has a planar unornamented interior surface.

FIG. 1

FIG. 2

FIG. 3

FIG. 4

FIG. 5

FIG. 6
